GUN HOLSTER

Harold A. Barrow, 1612 Cynthia Drive,
Rockford, Ill. 61107

Continuation-in-part of design application Ser. No.
129,305, Mar. 29, 1971. This application Mar. 1,
1972, Ser. No. 231,072

Term of patent 14 years

Int. Cl. D22—99
U.S. Cl. D22—13

FIG. 1 is a perspective view of a gun holster embodying my new design;

FIG. 2 is a front elevational view thereof;

FIG. 3 is a side elevational view as seen from the right of FIG. 2;

FIG. 4 is a rear elevational view thereof; and

FIG. 5 is a side elevational view as seen from the left of FIG. 2.

The dashed lines on the gun holster indicates stitching. The gun is shown in broken lines in FIG. 2 for illustrative purposes only.

This is a continuation-in-part of design application Ser. No. 129,305, filed Mar. 29, 1971 and now design patent Ser. No. 224,010.

I claim:

The ornamental design for a gun holster, substantially as shown and described.
